UNITED STATES PATENT OFFICE

134,184

DESIGN FOR A FOOD SERVICE BUILDING OR THE LIKE

John D. White, Wichita Falls, Tex.

Application May 22, 1940, Serial No. 92,528

Term of patent 3½ years

To all whom it may concern:

Be it known that I, John D. White, a citizen of the United States, residing at Wichita Falls, in the county of Wichita and State of Texas, have invented a new, original, and ornamental Design for Food Service Buildings or the like, of which the following is a specification, reference being had to the accompanying drawing, forming part thereof.

In the accompanying drawing:

Fig. 1 is a perspective view of the food service

building or the like showing my new design, and taken from the front end, the rear end being substantially the same in appearance except for the representation of the dogs; and

Fig. 2 is a top plan view thereof.

I claim:

The ornamental design for a food service building or the like, substantially as shown and described.

JOHN D. WHITE.
